Carriage-Spring.

No 8,244.

Patented July 22, 1851.

UNITED STATES PATENT OFFICE.

M. G. HUBBARD, OF ROCHESTER, NEW YORK.

CARRIAGE-SPRING.

Specification of Letters Patent No. 8,244, dated July 22, 1851.

To all whom it may concern:

Be it known that I, M. G. HUBBARD, of Rochester, in the county of Monroe and State of New York, have invented a new and useful Improvement in Carriage-Springs, and that the following is a full, clear, and exact description of the principle or character which distinguishes it from all other things before known and of the usual manner of making, modifying, and using the same, reference being had to the accompanying drawing, making a part hereof, in which—

Figure 1 is a side elevation and Fig. 2 a view of the under side.

My improvement consists in forming a spring of a straight bar of steel, of proper dimensions, and equal thickness throughout, attaching it to the carriage so as to be compensating and self adjusting to any weight that the carriage is capable of sustaining, by which means I form a durable, cheap, and efficient spring of great lightness, that cannot be set or made to strike when brought entirely down to its bearing.

The construction is as follows: The body of the carriage (a) is of any form, as the invention is equally applicable to a stage coach or buggy; the bottom of the carriage is made convex, like a rocker, either by making a sunk bottom of that form, or adding a piece of wood (b) for the purpose on each side of the carriage bottom; I then take two bars (c) of spring steel, of equal dimensions throughout, and of a size suitable for the

service, or instead thereof, wooden bars will answer the purpose. These bars are attached to the hind axle, one on each side, and passing along under the rockers (b) which rest on them, extend up in an inclined direction to the body of the carriage in front, where each is firmly bolted; at its extreme forward end similar bars (d) are in like manner affixed to the hinder end of the carriage, and passing along under the rocker (b) to the bolster forward, and there also attached, making a spring reach as in my former patent, but with this difference, that the bars, as they are brought down by weight in the carriage, bend around the curve of the rocker, and gradually grow shorter, and of course stronger, although the same size is maintained throughout, thereby getting rid of a great difficulty in construction which I have found in properly tapering the spring reaches of my former patent; a long staple (e) is put around the springs at the center of the rocker to keep them in place, and allow them sufficient play.

Having thus fully described my improved spring reaches for carriages, what I claim therein as new, and for which I desire to secure Letters Patent, is—

The combination of the rockers and spring bars of a carriage, substantially as herein set forth, and for the purposes described.

M. G. HUBBARD.
